UNITED STATES PATENT OFFICE.

WILLARD D. PADDOCK, OF KENT, CONNECTICUT.

DESIGN FOR A STATUE.

51,816.

Specification for Design.

Patented Feb. 26, 1918.

Application filed November 8, 1917. Serial No. 200,986. Term of patent 14 years.

To all whom it may concern:

Be it known that I, WILLARD D. PADDOCK, a citizen of the United States, residing at Kent, in the county of Litchfield and State of Connecticut, have invented a new, original, and ornamental Design for a Statue, of which the following is a specification, reference being had to the accompanying drawing, forming part thereof.

Fig. 2 is a side perspective view, and Fig. 3 is a perspective view from the opposite side of Fig. 2, and at a different angle.

I claim:

The ornamental design for a statue, as shown.

WILLARD D. PADDOCK.

Witnesses:

H. M. SEAMANS,
J. W. ANDERSON.
